UNITED STATES PATENT OFFICE.

BRUNO SCHMELZER, OF JERSEY CITY, NEW JERSEY.

PROPELLER.

1,331,586.

Specification of Letters Patent.

Patented Feb. 24, 1920.

Application filed June 26, 1919. Serial No. 306,898.

To all whom it may concern:

Be it known that I, BRUNO SCHMELZER, a citizen of the Republic of Poland, residing at Jersey City, county of Hudson, and State 5 of New Jersey, have invented certain new and useful Improvements in Propellers, of which the following is a specification.

This invention relates to a propeller adapted for use on aeroplanes, flying machines, dirigibles, motor boats or the like, the present invention being an improvement 10 on that disclosed in a prior patent issued to me on Sept. 12th, 1916, under No. 1,197,766.

15 The invention has for an object to provide a simple and efficient propeller construction by which a high degree both of tractive and lifting force may be exerted.

For further comprehension of the invention, and of the objects and advantages thereof, reference will be had to the following description and accompanying drawings, and to the appended claims in which the various novel features of the invention 25 are more particularly set forth.

Figure 1 of the drawings is a diagrammatic plan view showing a body or car with my improved propeller mounted thereon.

Fig. 2 is a detail plan view of the propeller and housing.

Fig. 3 is a side elevation with the housing partly broken away.

Fig. 4 is a detail cross section on the line 4-4 of Fig. 3.

35 My improved propeller may be mounted in any desired manner suitable to the structure to which it is applied being here shown as mounted on the upper ends of standards 1 which project inwardly from a body 2.

40 The propeller proper comprises a series of hollow vanes 3, of which four are here shown, which radiate from a hub 4. These vanes are approximately of rectangular shape in rear elevation with flat rear surfaces 5, the rear surface of the diametrically 45 opposed vanes being in alinement as shown. The vanes are of generally triangular shape, presenting in addition to the rear surface 5, the concaved side surfaces 6 and 7 which 50 incline inwardly toward one another.

The front, or advancing, side of each vane, forming the apex of the triangular vane structure, extends radially from the hub for about half of the length of the vane and 55 then curves backward as at 8 in a segmented curve which intersects the rear surface at

right angles. A supplementary triangular bead 9 extends around this curved portion of the vane structure centrally thereof, this bead decreasing in size from the extreme tip 60 of the vane and dying away substantially at the termination of the curved part.

The propeller may be driven by a suitable motor 10, carried on the car 2, through suitable drive connections such as the bevel 65 gear 11 on the shaft of the motor which meshes with a bevel gear 12 on the shaft 13 to which the hub 4 is fixed.

A semi-circular housing 15 co-operates with the propeller, this housing being of a 70 size and shape to closely inclose the propeller and being mounted concentrically thereto on the standards 1, the housing having hubs 16 which support the shaft 13 and which are in turn supported in suitable 75 bearings in the standards 1.

Fixed on one of the hubs 16 of the housing is a bevel gear 17 which meshes with a second gear 18 on the end of an oscillatory rod 19 carried in suitable bearings 20 in 80 the body 2 and having its opposite end located near the driver's seat 21 of the car and provided with a handle 22. By rotating the rod 19 the housing may be shifted around the propeller as desired. The rod 85 19 may be releasably locked by means of a detent 23 pivoted as at 24 to a fixed part and adapted to engage a toothed wheel 25 fixed to the rod.

As will be apparent the housing may be 90 shifted around the propeller to occupy any position desired so as to cause the vanes on the air to drive the vehicle either in a horizontal direction or to cause it to ascend or descend. 95

Having thus described my invention what I claim as new and desire to secure by Letters Patent, is:

1. In combination, a rotary propeller made up of a series of vanes presenting flat 100 radially extending rear surfaces, a semi-circular housing of a width and shape to closely inclose said vanes, and means for angularly adjusting said housing.

2. A propeller having a vane consisting of 105 a hollow structure of substantially triangular shape in cross section, with a flat rear surface extending transversely to the plane of rotation of the propeller and radially to the axis thereof. 110

3. A propeller having a vane consisting of a hollow structure of substantially tri-

angular shape in cross section, with a flat rear surface extending transversely to the plane of rotation of the propeller, and having concaved forwardly extending side surfaces.

4. A propeller having a vane consisting of a hollow structure of substantially triangular shape with the apex of the triangle on the advancing side of the vane, the rear side 10 of said vane being flat and extending radially for a distance from the base and then curving outwardly and rearwardly to meet the said rear side.

5. A propeller having a vane consisting of a hollow structure of substantially triangular shape with the apex of the triangle 15 on the advancing side of the vane, the rear side of said vane being flat and extending radially for a distance from the base and then curving outwardly and rearwardly to 20 meet the said rear side, the sides of the said triangle being concaved.

In testimony whereof he has signed his name to this specification, this 3rd day of June, 1919.

BRUNO SCHMELZER.
